(57) **CLAIM**

I claim the ornamental design for a device for filtering the intake air of an internal combustion engine, as shown and described.

DESCRIPTION

FIG. 1 is a top perspective view of the device for filtering the intake air of an internal combustion engine of my new design; FIG. 2 shows a different top perspective view thereof; FIG. 3 shows a side view thereof;

FIG. 4 shows a different side view thereof;

FIG. 5 shows a further different side view thereof;

FIG. 6 shows a bottom view thereof; and,

FIG. 7 shows a top view thereof.

The broken line showing of parts of the drawings is included for the purpose of illustrating use and environment and forms no part of the claimed design.
